UNITED STATES PATENT OFFICE.

EDWARD S. BLAKE AND HENRY H. BLAKE, OF PITTSBURG, PA.

ORE-CRUSHING MACHINE.

SPECIFICATION forming part of Letters Patent No. 226,964, dated April 27, 1880.

Application filed December 9, 1879.

To all whom it may concern:

Be it known that we, EDWARD S. BLAKE and HENRY H. BLAKE, of Pittsburg, in the county of Allegheny and State of Pennsylvania, have invented certain new and useful Improvements in Ore-Crushing Machines; and we do hereby declare the following to be a full, clear, and exact description of the invention, such as will enable those skilled in the art to 10 which it pertains to make and use it, reference being had to the accompanying drawings, in which—

Figure 1 is a longitudinal vertical section of our machine. Fig. 2 is a detail, showing the 15 devices for connecting the fly-wheel shaft to the toggles. Fig. 3 shows the relations of the toggle and toggle-block. Fig. 4 is a detail section, exhibiting the relations of the toggles, toggle-rest, anti-friction rollers, and pitman. 20 Figs. 5 and 6 are modifications.

In ore and rock crushing machines the great 25 weight required to withstand the pressure and the power necessary to move such masses and overcome their internal friction are obstacles to their adoption in many circumstances, and it is highly important to surmount them. Every 30 pound of steam saved and every particle of friction avoided become at once factors in the more economical construction and use of the machine.

To these ends our invention consists in so 35 constructing the parts and applying the power that the greater part of the internal work is done by rolling contact as distinguished from sliding or rubbing friction. The coefficient of the former being much less than that of the latter, a great gain in power is the necessary result.

Our invention further consists in the construction and combination of parts, as herein-after 40 fully described.

A is the frame; B, the fixed jaw; C, the movable or vibrating jaw, and D the eccentric of the fly-wheel shaft, all of the usual form and 45 relative location.

The toggle-seats A' in the frame A and jaw C differ from those commonly made. The toggle end is curved; but the toggle-block has a curve of greater sweep or radius, so that the 50 toggles E bear against the frame and vibrating jaw in rolling contact, whereas in the com-

mon form the toggle-seat accurately fits the convex end of the toggle, the contact thus being a rubbing or sliding one. This difference effects a great reduction of the friction, and, 55 in consequence, considerable economy in the power required to move the toggles against a given resistance. The adjacent ends of the two toggles are also slightly curved, and are so arranged as to bear directly upon each other, whereby the contact in operation is rolling, as distinguishable from the sliding friction at present met with in the accurately-fitted toggles and seats in the pitman. Here again we reduce the coefficient of friction and 60 diminish the power necessary to drive the jaw against a given resistance.

The usual eccentric, D, is arranged on the shaft of the fly-wheel. On top of this is a piece similar to the cap of a pillow-block, which, for 70 distinction, we term the "eccentric-box" g. Passing through the flanges of the box g are the ends of two headed bolts, h, whose heads support a plate, a, which has at its middle a transverse slot. This slot is long enough to 75 permit the passage of the bent ends of the U-shaped rod i when compressed together. When through the slot they spread outwardly, and are held in position by a wedge or key, k. The hooked ends of the rod thus are retained above 80 plate a. The lower end of rod i thence passes down through a slot in the toggles E and the toggle-rest I, which is constructed as follows, (see Fig. 4.) It is composed of two parts. Part l has transverse slots m, and is bolted to 85 the under part, n. Before bolting together small anti-friction rollers o are placed in the slots, the rollers being preferably somewhat smaller in diameter than the slots, but greater than the thickness of plate l, so as to project 90 slightly above its top. A slight dip is made in the top of the under block, n, so that rollers o will normally always roll to a given position. The rollers are located directly under the toggles E. Now, when the rest I is drawn upwardly by the revolution of the shaft, it lifts 95 the toggles, causing their convex ends to move together in rolling contact, and their contact with the rest I is also made rolling by the interposition of the rollers o.

The rest I has guards or flanges properly located, as shown, to preserve the position of 100

the toggles in cases of high speed or sudden relaxation of strain in the jaws. Rod *i* is held by a transverse key or bar, *s*, passing through its bend under the rest *I*.

5 Thus constructed, the bolts *h*, plate *a*, rod *i*, and rest *I* together constitute the pitman of the machine, whose length is adjusted by means of the top nuts, *h'*, thereby regulating the size of bite between the jaws.

10 If desired, a suitable dust-protector may be applied to these parts.

Such a machine has internally no rubbing or sliding friction whatever except that found between the eccentric and box. On the contrary, all the remaining parts are in rolling contact, and therefore the parts may be made less massive, and much less expenditure of power is required in driving them than when sliding friction is met with in operating.

15 In Fig. 6 the toggles are respectively concave and convex, with similar differences of radius to the before-described arrangement of toggle and toggle-seat.

In Fig. 5 another modification is shown, in which rod *i* is replaced by two separate bolt-rod, *i''*, with heads *m'* below the rest *I''*, and held together by the ring *n'* and bar *p'*.

20 In the above description, where we use the term "rolling contact" we mean a contact such as exists between a wheel in motion and the surface over which it travels, or that existing

between two wheels or rolls which bite on each other.

We claim as our invention—

1. In a crushing-machine, two toggles having their adjacent ends curved and in direct contact with each other, substantially as described, whereby the work is accomplished by rolling contact as distinguished from sliding friction. 35

2. In a crushing-machine, the combination, with the frame, vibrating jaw, and eccentric-shaft, of two toggles, having their adjacent ends curved and in direct contact, substantially as set forth. 40

3. The combination of the slotted toggles *E*, eccentric *D*, and cap *g* with the U-shaped rod *i*, connected to the cap *g*, the rest *I*, and the bar or bolt *s*, substantially as described. 45

4. The combination of toggles *E* and toggle-rest *I*, having the transverse rollers *o*, substantially as described. 50

5. The combination of cap *g*, nuts *h'*, bolts *h*, and slotted plate *a* with the rod *i* and wedge or key *k*, substantially as shown. 55

In testimony whereof we have hereto set our hands this 4th day of December, 1879.

EDWARD S. BLAKE.
HENRY H. BLAKE.
